STAMP VENDING MACHINES

William B. Fitzgerald, Chicago, Ill.

Application December 20, 1954, Serial No. 476,463

3 Claims. (Cl. 312—39)

This invention relates to novel improvements in vending machines, and more particularly in stamp vending machines.

A principal object of the invention is to provide in a stamp vending machine a novel and useful arrangement for vending postage stamps from a roll mounted within the machine, such arrangement embodying the feature for controlling the number of stamps to be vended.

Another and equally important object of the invention is the provision of an arrangement to prevent the stamps from becoming jammed in the track or stamp passage during the vending operation.

Another object of the invention is the provision of a simplified arrangement for facilitating severing the vended stamps from a web of stamps.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of a stamp vending machine embodying my invention;

Fig. 2 is a fragmentary sectional detail view taken substantially on line 2—2 of Fig. 1;

Fig. 3 is a fragmentary sectional detail view taken substantially on line 3—3 of Fig. 1;

Fig. 4 is a fragmentary perspective view of the stamp track embodied in my invention;

Fig. 5 is a fragmentary sectional detail view taken substantially on line 5—5 of Fig. 2;

Fig. 6 is a fragmentary sectional detail view taken substantially on line 6—6 of Fig. 4;

Fig. 7 is a perspective view of a pawl embodied in the invention;

Fig. 8 is a fragmentary perspective view of one of the stamp guide plates;

Fig. 9 is a perspective view of one of the plates of the stamp track or guide embodied in my invention and showing a modified form of construction;

Fig. 10 is an enlarged fragmentary perspective view of certain of the moving mechanism;

Fig. 11 is a perspective view of the web guide.

The several objects of my invention are preferably accomplished by the preferred form of construction shown in the accompanying drawings.

While the invention more particularly relates to a stamp vending machine, it will be apparent from the description to follow that the invention may be incorporated in vending machines of various descriptions and purposes.

2

The preferred form of construction of the invention, as shown in the drawings, includes a mounting plate 10. This plate 10 is mounted within an enclosure 11 comprising a removable back wall 12 and a front wall 13, the upper end 14 of which tapers inwardly and rearwardly toward the top wall 15. The bottom portion of the front wall tapers inwardly and downwardly as at 16 in a direction toward the bottom 17 of the enclosure 11.

10 The plate 10 may be mounted within the enclosure 11 in any suitable manner. Such plate 10 carries at its upper end portion a container 18 having a removable front wall 19. Within this container is adapted to be positioned a roll of stamps 20. The web 21 from the 15 roll of stamps 20 passes through a slot 22 formed in the cylindrical wall of the container 18. This web 21 extends downwardly and passes through a track or guide 23.

This guide 23 is mounted upon extensions 23' of the 20 plate 10 and comprises superimposed plates 24 and 25 secured together and providing therebetween a passage 26 for the web 21. The upper plate 25 includes an extension 26 having secured thereto as at 27 a spring finger 28, the lower end 29 of which is serrated to provide spaced teeth which yieldably bear upon the adjacent surface of the web to restrain the same from retraction from the guide 23.

The forward or opposite end portion of the upper 30 plate 25 terminates into a downwardly curved lip 30 having a straight edge 31. The lower plate 24 terminates just short of this curved lip 30 and is serrated to provide a plurality of spaced teeth 32 (Figs 4, 8 and 11).

An extension 23' provides a depending lip 33 which facilitates grasping of the vended stamps by reason of 35 the fact that when such stamps are grasped, the vended portion of the web is restrained by the lip 33 from moving rearwardly during the grasping operation.

To remove the vended stamp or stamps, the user grasps the vended stamps and pulls the same at an angle 40 against the teeth 32, which teeth will engage in the pre-formed perforations of the web and thereby facilitate the severing of the vended stamp or stamps from the remaining portion of the web.

The stamps are intermittently moved through the guide 45 23 by means of a plurality of fingers 34 arranged in parallel relation with respect to each other and pivotally mounted upon a pin 35 carried by a foot 36 of an arm 37. The fingers 34 are independently yieldably urged into stamp-engaging position by means of springs 38 (Fig. 6). By this arrangement, should there be any unevenness in the web of stamps or any defect in the perforations thereof, one or more of the fingers 34 will nevertheless engage the perforations of the stamp web 50 to facilitate the vending of the stamp or stamps.

55 To prevent the end of the web of stamps from striking against the edge 39 (Fig. 11) of the opening 40 through which the stamp engaging ends 41 of the fingers 34 pass, I provide in an elongated opening 42 provided in the upper plate 25, a wire 43 curved to conform to the curvature of the guide 23 and having its end terminating beneath the lip 30 as at 44. By this arrangement, 60 should the end of the web of stamps tend to curl upwardly at the point where it is intended to pass beneath the lip 30, the end of the wire 43 will prevent such curled end from finding passage upwardly through the opening 40 where it might otherwise jam the movement of the web of stamps. The arm 37, as shown in Fig. 2, is piv-

totally mounted on a pivot pin 45 provided by the mounting plate 10.

Mounted for pivotal movement on this pin 45 is an actuating disc 46. A slot and pin connection 47 provides operative connection between the disc 46 and the arm 37. On the arm 37 is a latching pawl 48 which is adapted to have latched engagement with a pin 49 carried by the mounting plate 10. The arm 37 is moved to the right as viewed in Fig. 2 by the action of a spring 50 connected to the arm 37 as at 51 and to the disc 46 as at 52. The pawl 48 is yieldably held in latched position by a spring 53. The pawl 48 has an angled end portion 54 (Figs. 2 and 7) which projects through a slot 55 formed in the arm 37. The end of the disc 46 is provided with an extension 56 which, when the disc 46 is rotated in an anti-clockwise direction as viewed in Fig. 2, will engage the angular end portion 54, pivot the pawl 48 from latched engagement with the pin 49, and free the arm 37 for pivotal movement to the right as viewed in Fig. 2, to dispose the foot of the arm 37 in position to engage the web of stamps, to move such web in an opposite direction when the arm 37 is moved in such direction. The movement of the arm 37 in a direction to advance the web of stamps through the guide 23 is accomplished by the engagement of the pin 47' of the slot and pin connection 47 in one end of the slot 48', at which time when the disc 46 is rotated in a clockwise direction, the pin 47' will act upon the arm 37 and pivot the arm in a direction to advance the web of stamps to the left, as shown in Fig. 2.

On the mounting plate 10 is removably positioned a lateral pin 57. The position of this pin is such that it will permit the foot of the arm 37 to engage the web of stamps at a point such that, when the web of stamps is advanced through the guide 23 to the left, as viewed in Fig. 2, two stamps will be vended to the purchaser.

By positioning the pin 57 in the opening 58, only one stamp will be vended. By positioning the pin 57 in the opening 59, three stamps will be vended. By this simple arrangement, the number of stamps to be vended by the machine may be changed from one to two or three by simply relocating the pin 57 in the proper opening. The pin 57 may be screw-threaded into the opening or it may be otherwise fixed to the mounting plate 10 as by means of a nut threaded upon the end thereof.

The disc 46 is provided with a handle 60 which moves through an elongated slot 61 formed in the front wall 13 of the enclosure 11. The movement of this disc 46 is normally restrained by a coin-actuated latching arm 62 provided with a latch finger 63 which is adapted to engage an extension 64 on the disc 46 to restrain the disc 46 from movement until a proper coin has been deposited in the slot 65.

A coin deposited in the slot 65 is, by channel 66, guided to a coin weighing plate 67 pivoted as at 68. If the coin is of proper weight, it will pivot the plate 67 out of blocking position of the outlet slot 69 of the channel, permitting the coin to drop to a guideway 70, where it will be deposited in a coin pocket 71 (Fig. 2) provided by an extension 73 of the disc 46 and the lower end portion of the guideway 70.

A coin positioned in the pocket 71 will, when the disc 46 is rotated in an anti-clockwise direction as viewed in Fig. 2, engage a lifting finger 74 provided by the latch arm 62. As the disc 46 is moved, the coin, by reason of engagement with this finger 74, will pivot the arm 62 in a clockwise direction as viewed in Fig. 2, against the action of a spring 75 to release the disc 46 for pivotal movement in an anti-clockwise direction. The coin is carried by the pocket 71 to an acceptance chute 76, from which the coin drops into a suitable coin box or the like (not shown).

To eject the coin from the pocket 71, there is provided a spring finger 77, the laterally bent end portion 78 of which is adapted to pass into an opening 79 formed in

the extension 73 and engage the coin in the pocket 71 and yieldably project the coin from the pocket into the guideway 70.

To assure that the disc 46 will make a full-stroke during the vending operation of a stamp or stamps and to prevent what is known as "milking" the machine by merely rotating the disc 46 back and forth, I provide a full-stroke device 80. In the present instance, this full-stroke device comprises an edge portion on the disc 46 providing a row of teeth 81 which, when engaging a pawl 82, cannot be rotated other than in an anticlockwise direction as viewed in Fig. 2, with the result that in order to return the disc 46 to its original starting position, the full vending stroke thereof must be completed. A full-stroke device such as that just described is well-known in the art and its function and purpose well understood.

A coin which is not of the proper weight will not tilt the plate 67, with the result that the coin will be returned to a coin return cup 83 provided on the front 13 of the enclosure 11.

In Fig. 9, I have shown a slightly modified form of construction with respect to the upper plate 25 of the guideway. In this construction, in lieu of the wire 43, I have provided a web 43' formed integral with the plate, as shown in Fig. 9. This web accomplishes the same function as the wire 43.

The several advantages of my invention will be clearly understood and appreciated from a reading of the foregoing description. I have provided a stamp vending machine by which a simple adjustment may vend one or more stamps; a machine which is positive in its operation; one which comprises a minimum number of parts, with the result that the machine can be manufactured at an economical cost.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A guide for a web of stamps vended from a roll comprising two superimposed plates providing therebetween a guide way, the bottom plate providing a serrated transversely extending edge at the dispensing end of said guide way, the top plate providing a downwardly curled lip in spaced confronting relation about said serrated edge for deflecting said web in a downward direction, said top plate having an elongated slot formed in a longitudinal direction therein and a member in said slot and extending longitudinally with respect thereto and terminating at a point beneath said lip and between said serrated edge and said lip to engage and deflect the web of stamps in a downward direction.

2. A guide for a web of stamps vended from a roll comprising two superimposed plates providing therebetween a guide way, the bottom plate providing a serrated transversely extending edge at the dispensing end of said guide way, the top plate providing a downwardly curled lip in spaced confronting relation about said serrated edge for deflecting said web in a downward direction, said top plate having an elongated slot formed in a longitudinal direction therein and a wire finger in said slot and extending longitudinally with respect thereto and terminating at a point beneath said lip and between said serrated edge and said lip to engage and deflect the web of stamps in a downward direction.

3. A vending machine comprising in combination, a guide for guiding the movement of an article to be vended in a longitudinal direction with respect to the guide, a manually rotatable disc carried within said machine, an article engaging member for moving said article in one

direction to be vended from said machine comprising an arm pivotally carried by said disc, means for pivoting said arm relative to said disc and in a like direction when said disc is rotated, means for releasably latching said arm against pivotal movement until said disc has been rotated the predetermined distance in one direction, a slot and pin connection between said disc and said arm to move said arm in a direction to vend said article from said machine, and a spring finger carried on said guide to prevent jamming of an article therein.
